UNITED STATES PATENT OFFICE.

HERBERT E. SHREEVE, OF MILBURN, NEW JERSEY, ASSIGNOR TO WESTERN ELECTRIC COMPANY, OF NEW YORK, N. Y., A CORPORATION OF ILLINOIS.

TELEPHONE REPEATER SYSTEM.

1,074,298.

Specification of Letters Patent. Patented Sept. 30, 1913.

Application filed February 24, 1912. Serial No. 679,553.

To all whom it may concern:

Be it known that I, HERBERT E. SHREEVE, subject of the King of England, residing at Milburn, in the county of Essex and State 5 of New Jersey, have invented a certain new and useful Improvement in Telephone Repeater Systems, of which the following is a full, clear, concise, and exact description.

This invention relates to telephone relay 10 or repeating systems, and more particularly to a system in which the repeating apparatus, including its local repeating circuit, is associated with the two ends of a link circuit in such manner that when the link circuit 15 is connected with the main circuits it constitutes a connection between the two main circuits uniting them into a single compound circuit for through communication.

20 One of the objects of this invention is to provide means for connecting a telephone receiver to the repeater circuit in such a manner that it will provide an adequate volume of receiving for supervisory purposes and will not appreciably shunt transmission and will not unbalance the repeater circuit. This is accomplished by providing a supervisory coil having one receiver winding in inductive relation to a plurality of line 25 windings connected on both sides of the circuit so that any differences in phase of the currents or current variation on opposite sides of the repeater will be readily indicated and reactive line disturbances will be 30 obviated.

Another object of this invention is to provide an efficient means for regulating or adjusting the repeater to operate on particular line combinations and to compensate for 40 certain variables such as a fluctuating battery voltage due to charge and discharge and high resistance of the transmitter element in the repeater itself due to continuous use. This is accomplished by changing the 45 phase relation of the input and output current of the repeater to the conditions of unbalance met with and regulating the output of the transmitting element to the same conditions. The means for accomplishing this 50 consists in placing a variable resistance in series with the magnetizing winding and

transmitting element of the repeater. The amount of resistance in series with the battery magnetizing winding and transmitting element regulates the output of the repeater 55 to any desired degree. The resistance is varied by means of a slide key which also controls the circuit through a relay to reverse the poles of the receiver for changing the phase relations of the input and output currents to the conditions of unbalance of the 60 line.

Another feature of this invention relates to the means provided for preventing the 65 humming of the repeater in case one end of the link is accidentally disconnected from the line. This feature consists in providing a relay in the third wire circuit or sleeve strand of the connectors, one of these relays being adapted when operated to put battery 70 on the repeater, the other being adapted to close the secondary coil which supplies current to the receiving element.

Another feature of this invention relates to the connection of the supervisory relay 75 whereby the balance of the system is maintained. This consists in bridging the supervisory relay at the center of the system in shunt of the repeater bridge. This accomplishes two things:—First, it renders the 80 system balanced and it provides a system in which the supervisory relay is equally sensitive to ringing currents from each side.

The drawing is a circuit diagram of the apparatus illustrating all of the features of 85 this invention in connection with a cord circuit.

Referring to the drawing, 5 and 6 designate three conductor plugs located one at each end of the repeater cord circuit and 90 adapted for insertion into jacks (not shown) of the long distance lines terminating in the same office as the repeater cord circuit. Connected in the tip and ring conductors 7 and 8 of the plugs 5 and 6, are 95 secondary windings 10 and 11 of a repeating induction coil, the primary 12 of which is connected with a source of current and the transmitter element of a repeater 15. The repeater 15 is preferably of the type shown 100 and described in U. S. Letters Patent No. 836,612 issued to me November 20th, 1906,

or my co-pending application Serial No. 329,261, filed May 25, 1911; and comprises a transmitter element 16, a receiver or operating winding 17 and a magnetizing winding 18. Connected with the middle point of the windings 10, and in series with a condenser 19, is a primary winding 20 of an induction coil 21, the secondary 22 of which is adapted for connection with the operating winding 17 of the repeater through contacts on a relay 23. Also connected with the middle point of the winding 11 in shunt with the repeater bridge and in series with a retardation coil 24, and a condenser 25, is a supervisory relay 26, the contact of which controls a slow-acting relay 27 which, when operated, locks up and completes a circuit for a supervisory lamp 28. The relay 27 is made sluggish in its operation by means of a copper sleeve or collar 29 for the purpose of preventing this relay operating upon discontinuous or momentary impulses of current such as result from the operation of telegraph apparatus connected with the line.

Connected in the sleeve strand 30 of the plug 5 is a relay 31 which is operated when the plug 5 is inserted into the jack of the desired line, and, when operated, closes contacts in the repeater bridge. In the sleeve strand 32 of the plug 6 is a relay 33 operated upon the insertion of the plug 6 into its jack. The relay 33 is adapted when operated to connect battery 34 with the transmitter element 16 of the repeater 15; also with relays 35 and 36, the relay 35 being adapted when operated to complete the repeater bridge, and the relay 36 being adapted to open a short circuit of the windings 10 and 11 normally maintained through the back contacts of said relay. In circuit with the battery 34 is a special switching key such as shown and described in my allowed application Serial No. 654,279, filed October 12, 1911. This key comprises in general four sets of contact springs 40, 40 of the same length, and one set of springs 41 shorter than the springs 40, 40, together with a longitudinally-movable reciprocating plunger 42, adapted in one position to be moved into engagement with the longer contact springs only, and in its other position to engage all of the contact springs. The operation of the longer contact springs 40, 40 completes a circuit from the battery 34 through resistance 43, 43 and the operation of the springs 41 completes a circuit for the pole changing relay 23.

Connected in the tip and ring conductors 60 of the cord on each side of the windings 10 and 11 are primary windings 50, 50 and 51, 51 of a repeating coil, the secondary 52 of which is adapted to be connected with the operator's receiver 53 through a key 54.

With this arrangement of windings on both 65 sides of the repeater, any differences in phase in the currents on opposite sides of the repeater will be readily detected in the blurred receiving which results. One pair of the windings 50, 51 is connected with one side 70 of a cut-off key 55, the other pair of said windings being connected with the other side of said key, the operation of this key enabling the operator to talk on to the line in either direction without interference from 75 the third party.

The telephone receiver 53 forms part of an operator's telephone set, comprising in addition a transmitter 58, local battery 59, and primary 60 of an induction coil, the 80 secondary 61 of which comprises two windings, one of which is adapted to be connected in series with the receiver, and in bridge of the tip and ring conductors of the cord by means of a "talk and listen" key 62. 85 The magnetizing winding 18 of the repeater is connected to ground through a retardation coil 65, and this coil 65, and winding 18 are shunted by a condenser 66; the function of the retardation coil 65 is to limit the flow 90 of current through the winding 18, and that of the condenser 66 to localize the microphone currents in the transmitter button and primary winding and to exclude such currents from the magnetizing winding 18. 95

Referring now to the operation of the apparatus and circuits, it will be assumed that the plugs 5 and 6 are inserted into the jacks (not shown) of the lines which are to talk through the repeater; with these plugs inserted, ground will be connected with the sleeve contacts thereof and circuits completed for the sleeve relays 31 and 33. The operation of the relay 31 closes its front contacts 80 and 81, and the operation of the relay 33 closes its contacts 82 and 83. The closing of these contacts is preliminary to the succeeding operation which is the movement of the key slide 42 into position to close the first pair of contacts 40. The closure of this pair of contacts completes two paths for current, one of which may be traced from the battery 34 through the contacts 82 and 83 of relay 33, conductor 84, contacts 40, resistance coils 43, 43, conductor 85, winding 12 of the induction coil of the repeater, conductor 86 to one electrode of the transmitter 16 of the repeater, through the commutated material to the other electrode thereof, conductor 87, conductor 88, magnetizing winding 18 of the repeater and retardation coil 65 to ground. The other of these paths is from battery 34, contacts 82 and 83 of relay 33, conductor 84, contacts 40, conductor 90 winding of relay 35, conductor 91 winding of relay 36, conductor 92, contact 93 of cut off key 55, conductor 94, contact 95 of cut off key 55, conductors

96 and 97, and contact 98 of "talk and listen" key 62 to ground. The first of these paths traced completes a circuit for the transmitter of the repeater while the second 5 completes an energizing circuit for the relays 35 and 36. The operation of relay 35 closes its contact 100 and completes a bridge of the cord conductors including the winding 20 of the coil 21. This circuit may be traced 10 from the middle point 101 of the winding 10, conductors 102 and 103, condenser 19, conductor 104, winding 20, conductor 105, contact 100 of relay 35, conductor 106, contacts 80 and 81 of relay 31, conductor 107, 15 conductor 108 and conductor 109 to the middle point 110 of winding 11. This constitutes the input circuit of the repeater and as will be noted, can only be completed when the plugs are in their jacks, thus preventing 20 the repeater from humming in case one of the plugs is accidentally pulled down. This feature is further guarded against by having the coils 10 and 11 normally short-circuited through normally-closed contacts 25 114 and 115 of the relay 36, which are opened when this relay operates.

In the operation of the repeater, voice currents coming over the line to the end of the plug 5 will find a path over the conductors 30 7 and 8, through normally closed contacts 116 of a ringing key 117, normally closed contacts 118 of the cutoff key 55 conductors 119, 120 through one set of windings 50, 51, conductors 121 and 122, conductors 123 and 35 124, the two left-hand halves of the windings 10 and 11, and the bridge of the coil 20 previously traced. This will induce currents in the winding 22 of the coil 21, which induced currents will cause the movable 40 polepiece of the repeater to vibrate. The vibrations of the movable polepiece and its attached electrode being made more forceful by the initial magnetization produced by current in winding 18. Assuming that 45 the pole changing relay 23 is in the position shown, the circuits for the induced currents will be from one side of the winding 22 over conductor 125, contact 126 of relay 23, conductor 127, conductor 128, conductor 50 88, winding 17, conductor 129, contact 130 of relay 23 and condenser 131 to the other side of the winding 22. The reciprocation of the plunger caused by the current in this last traced circuit will cause an agitation of 55 the comminuted material between the electrodes of the transmitter 16 and a consequent variation in the resistance of the circuit and the battery current through the winding 12 which will in turn induce a 60 current in the other halves of the windings 10 and 11, conductors 132 and 133, the other set of windings 50 and 51, conductors 134 and 135 normally closed contacts 136 of cutoff key 55, normally closed contacts 137

of ringing key 117 to conductors 7 and 8, 65 and to the line with which plug 6 is connected. The circuit under consideration being a two-way repeater circuit, it is clear that in talking from the end of the plug 6 the paths for the incoming and outgoing voice currents would be just the reverse of those 70 traced.

Referring now more specifically to the supervisory features of the system, it will be noted that when the key 54 is operated, 75 it connects the receiver 53 and winding 52 in series, the circuit being as follows: from one side of winding 52, conductor 150, contact 151 of key 54, conductor 152, conductor 153, receiver 53, conductor 154, conductor 155, contact 156 of key 54, and conductor 157 to the other side of the winding 52. This places the receiver 53 in condition to receive induced currents from the windings, 50, 50 and 51, 51 and any difference in phase of the currents on opposite sides of the repeater due to difference in the impedance upon the two sides of the repeater bridge will be indicated by blurred receiving, which results with the receiver in 85 inductive relation to the line upon both sides of the repeater bridge, the true condition of the circuit upon both sides of the repeater bridge will be indicated to the operator and the three requirements previously set forth 90 will be met.

The control of the repeater to compensate for certain variables met with such as fluctuating battery voltage due to charge and discharge, and high resistance transmitter 100 elements of the repeater due to continued use may be governed by regulating the output of the repeater and changing the phase relation of the input and output currents of the repeater to compensate for unbalanced 105 conditions of the line. This may be accomplished in various ways, such for instance as reversing the terminals of the primary winding 12 in the output circuit, reversing the terminals of the input winding 20 or 110 reversing the terminals of the operating winding 17 of the repeater. This last is the preferable method and the one shown on the drawing. To explain more fully, it is to be noted that the repeater is a polarized 115 instrument and the direction of movement of the transmitter plunger will therefore be dependent upon the polarity of the repeater operating current. There is naturally a slight lag in the transmitter element, due 120 to the inertia of the parts, and it may well happen, and frequently does in practice, that due to the polarity of the operating current and the inertia of the movable parts, the repeater current is approximately 90° behind 125 the operating current, under which condition a condition of unbalance between the line and the repeater circuit results, and the

currents in these two divisions will cancel each other. The reversal of the polarity of the repeater will change the phase relation of the repeater current to co-act with that of the operating current so that instead of opposing or canceling, these currents will be in a proper phase with respect to each other to produce the best conditions for talking.

- 10 Referring first to the means for regulating the output of the receiver, it will be noted that the advance of the slide member 42 into engagement with the last three of the sets of springs 40, 40 short circuits the 15 resistance elements 43, 43 in series with the battery 34 and the transmitter element 16 and magnetizing coil 18 of the repeater 15, thus increasing the current and regulating the output of the repeater. The other feature of the adjustment, namely that of changing the phase relation of the output and input currents of the repeater to the unbalanced condition of the line, is accomplished by the actuation of the set of contacts 41 by 20 depressing the slide member into the position indicated in dotted lines on the drawing and moving it into engagement with the said contacts. The closure of the contacts 41 completes a path for current which may 25 be traced as follows: from battery 34, contacts 82 and 83 of relay 33, conductor 84, contact 41, conductor 160, and a winding of relay 23 to ground. Current in this path 30 operates the relay 23 opening its back contacts 126 and 130 and closing its front contacts 161 and 162 thus reversing the poling of the operating winding 17. The slide key is so arranged that the plunger member 42 cannot be depressed in any except its normal position, or when it is entirely free from 35 engagement with the contact springs, thus making it impossible to change the poling of the receiving element with the full battery current through the output circuit.
- 40 45 When the "talk and listen" key 62 is operated, it breaks ground contact and closes contacts 165, 165 and connects the secondary 50 55 winding 61 of the induction coil across the line at the middle points of the windings 10 and 11 with the receiver in series with one of the windings and in parallel with the other. The bridge will be as follows: from the middle point 110 of winding 11, conductor 109, conductor 167, contact 165 of key 62, conductor 168, 60 secondary winding 61, windings 169 and 170, conductor 171, normally closed contact 172 of monitoring key 54, conductor 155, condenser 173, conductor 174, the other contact 165 of key 62, conductor 175, conductor 176 and conductor 102 to the middle point 101 of winding 10. The receiver 53 is connected with the middle point of the winding 61 and one side of the condenser 173. The breaking of the ground contact opens the circuit for re-

lays 35 and 36, thus rendering the repeater 65 inoperative.

In the operation of the supervising relay 26, ringing current coming from either end of the line, will come in over one side of the line to the middle point 101 of winding 70 10, through conductor 102, conductor 176, conductor 180, winding of relay 26, condenser 25, retardation coil 24, conductor 108, conductor 109 to the middle point 110 of winding 11 and back over the other side of the line. Current in this path will energize 75 relay 26, causing it to operate and close its contact 181, thus completing a circuit for the relay 27, which may be traced from battery 34 through the winding of the relay 80 27, conductor 182, contact 181 of relay 26, conductor 183, conductor 184, conductor 97 and contact 98 of the "talk and listen" key to ground. Current in this circuit operates 85 the relay 27 to close its contacts 185 and 186, which closes a circuit for the relay winding and supervisory lamp which is the same as that just traced, except that conductor 187 is substituted for the path through the contact 90 181 of relay 26. Current in this last-named circuit retains the relay 27 in its operated position, and the supervisory lamp 95 28 lighted until the talk and listen key 62 is operated. The combined impedance of the retardation coil 24, condenser 25 and relay 26 is such that the circuit including them 100 will afford a ready path for the ringing currents, but will not appreciably shunt the talking currents. The operation of the ringing key 117 short circuits the operating coil 100 17 of the repeater, this short circuit being established through contact 190 in one position of the ringing key, and through contact 191 in the other position of said key.

I claim:

1. In a telephone repeating system the combination with link conductors, of a repeater circuit bridged between said conductors, current inducing windings connected in said conductors on both sides of said repeater bridge, a secondary winding in inductive relation to said current inducing windings and a receiver in circuit with said secondary winding. 105
2. In a telephone repeater system, the combination with link conductors, of a repeater circuit bridged between said conductors, a pair of current inducing windings connected in each of said conductors one on each side of said repeater circuit, a secondary winding in inductive relation to said current inducing windings, a receiver and means for connecting said receiver in circuit with said secondary winding. 110
3. In a telephone repeating system the combination with link conductors, of switching means for connecting the opposite ends of said conductors with line wires, a re- 115 120 125

peater circuit adapted to be bridged between said link conductors, and switching means under the joint control of the link connecting means for completing said repeater circuit bridge.

4. In a telephone repeating system the combination with link conductors, of switching means for connecting the opposite ends of said conductors with line wires, a telephone repeater, a circuit for said repeater, electromagnetically controlled switching means for bridging said repeater circuit between said link conductors, a switching key, and a source of current the connection of which with said electromagnetic switching means and said repeater is under the joint control of said switching means and said link connecting means.

5. In a telephone repeating system the combination with link conductors of switching means for connecting the opposite ends of said conductors with line wires, a repeater circuit, relays for connecting said repeater circuit in bridge of the link conductors, the operation of one of said relays being under the control of one of said link connecting means and the operation of the other of said relays being controlled by the other of said link connecting means.

6. In a telephone repeating system the combination with link conductors, of switching means for connecting the opposite ends of said conductors with line wires, a repeater, secondary windings in said link conductors adapted to receive induced currents resulting from the operation of said repeater, a relay, and contacts controlled by said relay normally short circuiting said secondary windings, the operation of said relay being under control of one of said link connecting means.

7. In a telephone repeating system the combination with link conductors, of switching means for connecting said conductors with line wires, a repeater, input and output circuits for said repeater, and electromagnetic switching means operated in the making and unmaking of connections of said link conductors with the lines to control the association of said input and output circuits with said link conductors.

8. In a telephone repeating system the combination with a three-wire connecting circuit comprising tip, ring and sleeve conductors, of connecting means associated with each end of said connecting circuit, a relay in each of the sleeve wires operated in the making and unmaking of connections with the corresponding connecting means, a repeater, an input circuit for said repeater adapted to be bridged between the tip and ring conductors of said connecting circuit, said bridge being controlled by both said sleeve relays, and an output circuit for said

repeater controlled by one of said sleeve relays.

9. In a telephone repeating system the combination with link conductors, of a telephone repeater having an input winding inductively related to said link conductors, an energizing circuit for said repeater, and means for controlling the poling of said input winding and means for controlling the amount of energy in said energizing circuit.

10. In a telephone repeater system the combination with telephone lines, of link conductors for connecting said telephone lines, a telephone repeater operatively associated with said link conductors, and means for changing the phase relation of the input and output currents of said repeater to compensate for unbalanced conditions of said line.

11. In a telephone repeating system the combination with link conductors, of a telephone repeater, input and output circuits for said repeater operatively related to said link conductors, and means for reversing the polarity of current in one of these circuits with respect to the currents in the other of said circuits.

12. In a telephone repeating system the combination with link conductors, of a telephone repeater having an operating winding inductively related to said link conductors and means for reversing the polarity of current through said operating winding.

13. In a telephone repeating system the combination with link conductors, of a telephone repeater, an operating winding therefor, an induction coil secondary winding in circuit with said operating winding, the primary winding of said coil being connected in bridge of said conductors, a pole changing switch in said secondary circuit and means for operating said pole changing switch.

14. In a telephone repeating system the combination with link conductors, of an induction coil primary winding adapted to be bridged between said conductors, a telephone repeater, an operating winding therefor, a secondary winding for said induction coil in circuit with said operating winding, pole changing contacts in said circuit, a relay for controlling said contacts and a manually operated switch for controlling the circuit of said relay.

15. In a telephone repeater system the combination with link conductors, of a telephone repeater having an operating winding in inductive relation to said conductors, a pole changing relay for said operating winding, an output circuit for said repeater, a source of energy therefor and for said pole changing relay, and a two-position key adapted in both positions to vary the energy of the output circuit and in one position

only to control the circuit of the pole changing relay.

16. In a telephone repeater system the combination with link conductors, of induction coil secondary windings connected in said conductors, a telephone repeater circuit in bridge of said conductors at the middle points of said secondary windings and a supervisory relay connected in bridge of said

secondary windings in shunt with said repeater bridge. ¹⁰

In witness whereof, I hereunto subscribe my name.
